UNITED STATES PATENT OFFICE.

JOSEPH MORENO, OF LOS ANGELES, CALIFORNIA, ASSIGNOR OF ONE-HALF TO ALBERT MALLNER, OF LOS ANGELES, CALIFORNIA.

CENTER SUPPORT.

Application filed May 18, 1925. Serial No. 31,047.

To all whom it may concern:

Be it known that I, JOSEPH MORENO, a citizen of the United States, residing at Los Angeles, in the county of Los Angeles and State of California, have invented certain new and useful Improvements in Center Supports, of which the following is a specification.

This invention is a device adapted to be readily fixed in the bore of a casting or the like, in order to provide a support for the center of dividers, compasses, or the like which are used in measuring or describing a circle around the bore of the casting.

It is the object of the invention to provide a device of extremely simple construction which may be quickly expanded for frictionally holding the same in a bore around which a circle is to be described, and which may be readily adjusted to fit in bores of a wide range of size.

It is a still further object of the invention to form the device of a relatively hard material for the desired durability, and to provide a working surface of relatively soft material adapted to be engaged by the centers of compasses and like instruments without injuring the points thereof.

It is a still further object of the invention to provide an instrument having relatively narrow contact ends, so that it may be placed in a bore with the contact ends in close proximity to the walls thereof, in order that the contact ends may frictionally engage in the bore by relatively slight longitudinal expansion of the tool.

The invention will be readily understood from the following description of the accompanying drawings showing one practical embodiment of the invention:

Fig. 1 is a plan view showing the method of using the device in a relatively small bore.

Fig. 2 is a similar view showing the device adjusted for use in a larger bore.

Fig. 3 is a transverse section on the line 3-3 of Fig. 2.

Fig. 4 is a perspective view of the device.

The tool is adapted to be mounted in any bore, and may be adjusted in length to any desired size and then longitudinally expanded to frictionally clamp the same in the bore and thus form a support for the center of compasses, dividers, or similar instruments.

The device preferably comprises a metal block 1 having projecting contact ends 2 of reduced width, with the major portion of the upper surface of block 1 recessed to receive a layer of relatively soft material 60 such as lead 3.

Expanding means shown as a screw 4 is threaded into one of the contact ends 2, and is preferably provided with a head 5 for turning the same. A contact plate 6 may 65 be mounted on the end of the screw so as to prevent axial displacement of said plate while permitting turning of the screw relative thereto.

The tool as thus described is used in relatively small bores, the narrow contact ends 2 permitting insertion of the device in a bore so that slight turning of screw 4 will frictionally clamp contact plate 6 and the opposite end contact 2 against opposite 75 walls of the bore and thus hold the support against displacement with the center of the bore at some point on the working surface 3. A circle may then be described around the bore by centering the compasses on the 80 surface 3 of the support, the use of a relatively soft material for the working surface preventing injury to the points of the instruments which are used as a measuring or scribing medium.

End extensions are provided for block 1 to adapt the device to bores of greater diameter, the end extensions being supplied in various lengths for any desired adjustment. The end extensions are shown as 90 yokes 7 having arms slidably engaging the sides of block 1 by means of tongue and groove connections 8. Shoulders 9 of the yokes abut against the ends of block 1 at the sides of the projecting contact ends 2, 95 and the bases 10 of the yokes extend around the projecting contact ends in spaced relation therefrom so that head 5 of the expanding screw may project through one of said spaces and thus adapt the end extensions 100 for interchangeable use upon the respective ends of block 1.

The end extensions have projecting ends 2^a of different lengths and of narrow width similar to contact ends 2, so that block 1 105 with end extensions mounted thereon may be received in a bore with the contact surfaces of ends 2^a relatively close to the wall of the bore in order that slight turning of screw 4 will expand the device so as to 110

clamp the same in the bore, the expansion being accomplished by the abutment of contact plate 6 against the base 10 of the extension yoke.

- 5 In practice extension yokes having ends 2^a of the desired length to adapt the support to the size of the bore are mounted on either one or both ends of block 1 so that some point on working surface 3 will be at 10 the center of the bore, and screw 4 is then turned to longitudinally expand the structure for clamping the same in the bore, the contact surfaces which may engage the walls of the bore including plate 6, and ends 2 and 2^a, depending upon the use of yokes 7 at one or both ends of block 1.

It will be apparent that various changes may be made in the construction, combination, and arrangement of parts as thus 20 described without departing from the spirit of the invention.

I claim:

1. A device of the character described 25 adapted to be received in a bore and comprising a supporting surface for the centers of compasses or the like, and a screw threaded in the end of the device and having an end contact plate adapted for turning of the screw relative thereto without axial dis- 30 placement of the plate from the screw whereby turning of the screw will engage the contact plate and the opposite end of the device with the wall of the bore for clamping the supporting surface in the bore.

- 35 2. A device of the character described adapted to be received in a bore and com-

prising a supporting surface for the centers of compasses or the like, a screw threaded into an end of the device, and interchangeable end extensions slideable relative to the 40 supporting surface, said end extensions extending around the screw for access thereto and adapted for abutment against the supporting surface and expansion by the screw for longitudinally expanding the device. 45

3. A device of the character described adapted to be received in a bore and comprising a supporting surface and an end projection adapted for longitudinal adjustment by turning thereof relative to the supporting surface, said longitudinal projection having an end contact plate adapted for turning of the longitudinal projection relative thereto, whereby turning of the longitudinal projection will engage the contact plate and the opposite end of the device with the wall of the bore for clamping the supporting surface in the bore. 55

4. A device of the character described 60 adapted to be received in a bore and comprising a supporting surface and an end projection adapted for longitudinal adjustment by turning thereof relative to the supporting surface, and an end extension slideable relative to the supporting surface and received over the longitudinal projection for expansion relative to the supporting surface by turning of the longitudinal projection. 65

In testimony whereof I have affixed my signature to this specification.

JOSEPH MORENO.
